UNITED STATES PATENT OFFICE.

HENRY A. WISE WOOD, OF NEW YORK, N. Y., ASSIGNOR TO CAMPBELL PRINTING PRESS & MANUFACTURING COMPANY, OF NEW YORK, N. Y., A CORPORATION OF NEW YORK.

HANDLING OF WEB-ROLLS.

SPECIFICATION forming part of Letters Patent No. 794,577, dated July 11, 1905.

Application filed March 4, 1898. Serial No. 672,555.

To all whom it may concern:

Be it known that I, HENRY A. WISE WOOD, a citizen of the United States, residing at New York, in the county of New York and State of New York, have invented new and useful Improvements Relating to the Handling of Web-Rolls, of which the following is a specification.

This invention relates to that class of printing-machines in which the supply of paper or material to be printed is drawn from a web-roll or web-rolls. In a machine of this character much time is lost in supplying the machine with a fresh web-roll to take the place of a roll from which the web has been drawn. This is especially the case in large printing-machines, where the supply is taken from a number of web-rolls. The way ordinarily practiced to introduce a fresh web is as follows: When the web-roll in the machine has expired, the machine is stopped, the web is cut by hand from the expired web-roll or "stub," as it is sometimes called, and the expired web-roll is removed by hand from the machine. Then a fresh web-roll is placed by hand in position, the end of the web drawn therefrom by hand and pasted by hand to the last end of the web which was drawn from the expired web-roll. Then the machine is started slowly in operation and the fresh web drawn into the machine. This operation takes a number of minutes, and thereby occasions the loss of a large number of printed papers.

By this invention mechanism is provided whereby the end of the fresh web can be attached to the web in the machine, and the same is preferably arranged so that the operation can take place without stopping the printing-machine. Mechanism is also provided for cutting off the web in the machine from the expiring web-roll as the fresh web is introduced into the machine, and further devices are provided so that the fresh web-roll can be very expeditiously placed in position.

Referring now to the drawings, which show in detail the best way now known for the carrying out of the invention, Figure 1 is a sectional view of part of a printing-machine with

the improved device applied thereto. Fig. 2 is a sectional view of a fresh web-roll, illustrating the way the supporting-shaft is applied thereto. Fig. 3 is a side view of the printing-machine, showing the devices by which the invention is carried out. Fig. 4 is an end elevation showing the mounting of the web-roll. Fig. 4^a is a detail of the device for adjusting the web-roll longitudinally. Fig. 5 is a detail view of the shearing-knife. Fig. 6 is a perspective view of a part which is termed the "tucker;" and Figs. 7 to 10, inclusive, are diagrammatic views illustrating the way the invention is carried out.

Referring to the drawings and in detail, 11, 12, 13, and 14 designate the cylinders of an ordinary form of web-printing machine. 15 designates a roll or guide for directing the web to the printing mechanism.

D designates a drawing-in or web-forwarding device for drawing the web into the machine. This consists of a drum 16, rolls 17 and 18, which bear thereon, and tapes 20, which run around said drum and rolls and around a series of tightener devices 19. The drum and rolls are positively driven by any suitable gearing from any moving part of the machine, so that the drum 16 and the rolls 17 and 18 will turn at the same peripheral speed as the web moves through the various mechanisms.

29 designates one of the side frames of the machine. In these side frames is mounted a shaft 21, projecting from which are a number of arms 22, to the ends of which is secured a tucker 23, which preferably has a number of small pins 24 projecting from the upper edge thereof. Also mounted on the shaft 21 is a handle 210. These parts are so arranged and centered that when the handle 210 is depressed the tucker 23 will be forced into the bite between the drum 16 and the roller 17. Also mounted in the frames is a shaft 25, upon which is mounted a blade or knife 26, which has pointed serrations 260. A spring 261 is used to keep said knife normally in the position shown in Fig. 3. Projecting from said shaft 25 is an arm 27, which is arranged in position to be struck by the end of the blade

23 as the same is moved upwardly to swing the knife 26 to engage the web *w*.

30 designates one of the shafts on which the web-rolls are mounted. Rigidly secured 5 on said shaft is a cone 31 and a gear 32. Fitting on the other end of the shaft is a cone 33, which may be made in the usual way in two split interlocking sections and which may be secured in place by means of a nut 34. 10 This shaft 30 is inserted in the right-hand end of the web-roll, as shown in Fig. 2, the cone-sections 33 applied thereto, and the nut 34 then tightened up on the cone-sections, so that the web-roll will be nicely held and centered 15 on the shaft 30.

35 designates a runway or guide formed on the end of each frame by which a fresh web-roll *W'* may be rolled into the machine and slightly lifted to engage notches 36. From 20 the notches 36 the frames are slightly inclined downward, as at 37, to form guideways or tracks, so that if the web-roll is lifted out of the notches 36 the same will run down said guideways and drop into notches 38, which 25 notches 38 form the bearings for the web-roll when in the final operative position. Arranged in connection with each notch is a latch 39, which is adapted to engage the top of the shaft 30 when the same drops into said 30 notches, and the head of the latch 39 is inclined, so that when the shaft 30 drops into said notches the same will move the latch to one side, so that the shaft 30 can automatically drop into its proper position. Springs 35 41 are used to keep the latches normally in engagement with the top of the shaft 30. A latch is preferably used on each of the two side frames. The latches are pivoted on suitable studs 40. Each latch connects by a link 40 42 to a handle 44, mounted on a shaft 43, which is fitted in the side frames 29 and which extends across the machine, so that by moving the handle 44 to the right the latches 39 can be disengaged from the shaft 30.

45 45 designates a gear which has conical or guiding flanges 46 46 on each side thereof. The gear and flanges are mounted on a shaft 47, which is journaled in a lug projecting down from one of the side frames 29 and also, 50 if desired, in bracket 57. On the shaft 47 is arranged a brake-disk 48, co-operating with which are the two shoes 49 of a suitable brake. These shoes are hung on a shaft 54, the ends of which are tapped into the side frame 55 and into the bracket 57, projecting therefrom. Secured on this shaft is a suitable hand-wheel 55 and a collar 56. By turning the hand-wheel 55 the gear 45 and its side flanges can be adjusted axially, and when the gear and 60 flanges are adjusted axially in this manner the same motion will be imparted to the gear 32, and thereby to the web-roll, which is in position, and by this means the slight axial adjustment sometimes necessary for the web-roll can be obtained. This adjustment is ob-

tained as follows: When said hand-wheel 55 is turned, the shaft 54 is moved bodily either in or out. The brake-shoes 49 49 being loosely hung on the shaft 54 between said hand-wheel 55 and collar 56 will be constrained 70 to move with said shaft. These brake-shoes fitting on said brake-disk 48 will move said brake-disk, and thereby the shaft 47 will be moved axially, and as the gear 45 and its flanges 46 46 are attached to said shaft 47 they 75 will have to move therewith, and the flanges 46 46 will thereby adjust the gear 32. As the gear 32 is secured on the shaft 36 of the web-roll, the web-roll will be moved axially. This adjustment is usually only a slight one and is 80 provided for the purpose of bringing the web laterally or sidewise to proper position in the press. A shaft 50 is loosely mounted in bearings 52, and one end of the same is threaded into one of the brake-shoes 49, and a collar 53 is secured thereon to bear on the other brake-shoe. Mounted on this shaft 50 is a hand-wheel 51, by turning which the bite of the brake-shoes 49 on the disk 48 can be adjusted. This brake is used to provide a resistance to 90 the unwinding of the web, so that the web can be kept at the proper tension.

A feature of the invention will be seen when it is noted that the fresh web-roll *W'* will drop into its bearings 38, will be properly 95 held therein by the latches 39, and as this action takes place the gear 32, which is connected with said web-roll, will also drop into position to properly engage the gear 45, and thus the braking device. The cone 31 may 100 be grooved or notched, if desired, so as to obtain a good bite on the web-roll *W'*.

The way the device is used is as follows: As the machine is in operation and while the operators have plenty of time a fresh web-roll *W'* is placed in the notches 36. The end of the web from this fresh web-roll is accurately cut or squared and the end thereof is doubled back and the same placed over the tucker-blade 23, the pins 24 tightly holding 110 the web on this crease. A line of paste is applied to the fresh web just below the crease and at the point indicated by 230 in Fig. 3. Considerable slack is then drawn off from the web-roll *W'* and let out to the left, as shown 115 in Fig. 7. This is all done while the machine is in full operation, the web in the machine being drawn from the expiring web-roll *W*, the parts then assuming the position shown in Fig. 7. When all the web that is desired 120 is drawn from the roll *W*, the machine is put on its slow speed and the tucker 23 forcibly brought into the bite of the drum 16 and the roll 17. As the tucker is moved up the knife 26 will be brought into position to bear on the 125 web *w* drawn from the expiring web-roll *W*, and this web will be cut off, as indicated in Fig. 8. At the same time the end of the fresh web *w'* will be pasted onto the last end of the web *w*, and the pasted joint will be put under 130

pressure by passing through the bite between the drum 16 and the roll 17 and the drum 16 and the roll 18. After this operation takes place the web w' will then be drawn in from the drawing-in device, the tucker 23 of course being moved out of the bite as soon as the end of the fresh web w' is pasted to the last end of the web w . The expired web-roll or stub W is then removed from the machine, leaving the parts as shown in Fig. 9. Then the web-roll W' is lifted out of the notches 36 and given a push forward, when it will run down the guideways 37 and will drop into its bearings 38, be held therein by the latches 39, and the gear 32 will engage the gear 45, and thereby the braking device. As the web-roll runs down the inclines 37 it will be started turning in the proper direction, so that there will be no sudden pull put thereon as the web tightens between the drawing-in device and the web-roll. The operator of course properly manipulates the braking device so that the fresh web-roll will be properly started in action. All this can be done very rapidly and without stopping the machine, for just so soon as the pasted joint has been drawn through the machine at the slow speed the machine can be put back at full speed. Thus by this mechanism a great deal of time can be saved.

Other forms of braking devices, adjusting devices, and bearings for the web-rolls may be used.

Many other devices may be designed to carry out the broad purposes of the invention, and the invention may be applied, of course, to any form of machine in which the supply is drawn from a web roll or rolls.

Having thus fully described the invention, what is claimed is—

1. The combination of two sources of web-supply, mechanism for attaching the end of the fresh web to the expiring web and connections for operating said mechanism.
2. The combination of two sources of web-supply, with mechanism for attaching the end of the fresh web to the expiring web, and connections for operating said mechanism arranged so that the fresh web can be drawn forward without stopping the movement of the expiring web.
3. In a device for the purpose specified, means for providing a new source of web-supply, and means for discontinuing an expiring source of web-supply.
4. The combination with a web-forwarding device, means for providing a new source of web-supply, and means for discontinuing an expiring source of web-supply.
5. The combination of a web-forwarding device, of means for connecting the end of a fresh web to an expiring web, and means for discontinuing the supply of the expiring web.
6. The combination of a web-printing press, with means for providing a new source of web-

supply, and means for discontinuing an expiring source of web-supply.

7. The combination with a web-printing press of a device for forwarding the web from the roll to the press, and mechanism for connecting the end of a fresh web to an expiring web.

8. The combination with a web-printing press, a forwarding device for forwarding the web from the roll to the press, means for connecting the end of a fresh web to an expiring web, and means for discontinuing the expiring source of web-supply.

9. The combination of a web-forwarding device, means for attaching a pasted end of a fresh web to an expiring web, and connections for operating said means.

10. The combination with a web-printing press, of a device for forwarding the web from the roll to the press, with means for applying the pasted end of a fresh web to an expiring web, so that the forwarding device will press the joint together, and means for discontinuing the expiring source of web-supply.

11. The combination with a printing-machine in which the supply is drawn from a web, of means for attaching the end of a web drawn from a fresh web-roll to the web in the machine drawn from an expiring web-roll, and means for cutting off the web in the machine from the expiring web-roll.

12. The combination with a drawing-in device for drawing or unwinding a web from a web-roll, of means for attaching the end of a fresh web to the web which is being drawn from an expiring web-roll, and for simultaneously cutting off the web drawn from the expiring web-roll.

13. The combination with a drawing-in device adapted to draw or unwind the web from a web-roll, and a tucker to which the end of the web from a fresh web-roll can be secured, said tucker being mounted so that the same can be moved to tuck the end of the web drawn from the fresh web-roll into the drawing-in device.

14. The combination of a drawing-in device for drawing in or unwinding a web from a web-roll, a tucker to which the end of the web drawn from a fresh web-roll can be secured, said tucker being mounted so that the end of said fresh web can be tucked into the drawing-in device, and means for cutting off the web drawn from the expiring web-roll simultaneously with the introduction of the fresh web into the drawing-in device.

15. The combination with a set of bearings for a web-roll, of a drawing-in device for unwinding the web from the web-roll, means for attaching the end of the web drawn from a fresh web-roll to the web drawn from an expiring web-roll, and for cutting off the expiring web, and guides arranged so that after the expired web-roll has been removed, the fresh web-roll can be moved into said bearings.

16. The combination with a drawing-in de-

vice of a pivoted tucker for introducing the end of the fresh web, a pivoted knife for cutting off the old web, and means whereby the tucker and knife will act simultaneously.

5 17. The combination with a web-printing press, of a web-forwarding device for forwarding the web from the roll to the printing-press, a tucker for introducing the end of a fresh web, and pins mounted on the entering side of the 10 tucker.

18. The combination of a drawing-in device, a tucker for introducing the end of a fresh web, a pivoted knife normally held out of operation, and means whereby when the tucker is moved 15 to introduce the end of the fresh web, the pivoted knife will be brought into operative position.

19. The combination of the side frames, notches cut therein so that a web-roll can be 20 temporarily laid therein, bearings or notches formed therein in which the web-roll rests while in action, and braking devices carried by said side frames for controlling the unwinding of the web-roll in this last position, 25 which said web-roll will engage and operate when in the second set of bearings or notches.

20. The combination of the side frames having bearings, a web-roll having a gear mounted to turn therewith, a braking device carried by the side frame and having a gear connected 30 to actuate the same, the parts being arranged so that when the web-roll is placed in position in the bearings the gears will be engaged and the braking device will be attached to the web-roll.

21. The combination with the shaft of a web-roll, a gear mounted thereon, a braking device operated from a second gear, flanges as 46 46 arranged on each side of this second gear, and means for adjusting this second gear and 40 flanges axially.

22. The combination with the shaft of a web-roll, a gear mounted thereon, a second gear, braking devices actuated from the second gear, and means for adjusting the web-roll laterally. 45

In testimony whereof I have hereunto set my hand in the presence of two subscribing witnesses.
